UNITED STATES PATENT OFFICE

156,837

OPENWORK FABRIC SOAP CONTAINER

Raymond H. M. Orr, New York, N. Y.

Application August 10, 1948, Serial No. 148,040

Term of patent 7 years

(Cl. D4—3)

To all whom it may concern:

Be it known that I, Raymond H. M. Orr, a citizen of the United States and resident of New York, New York, have invented a new, original, and ornamental Design for an Openwork Fabric Soap Container, of which the following is a specification, reference being had to the accompanying drawing, forming a part thereof.

Fig. 1 is a plan view of the fabric container, showing my new design;

Fig. 2 is a side view;

Fig. 3 is a front view taken from the left of Fig. 2.

I claim:

The ornamental design for an openwork fabric soap container, as shown.

RAYMOND H. M. ORR.
